CLAIM

The ornamental design for a gift presentation device, as shown and described.

DESCRIPTION

FIG. 1 is a perspective view of the gift presentation device showing my new ornamental design;

FIG. 2 is a left side elevational view;

FIG. 3 is a top plan view;

FIG. 4 is a front elevational view;

FIG. 5 is a right side elevational view;

FIG. 6 is a rear elevational view; and

FIG. 7 is a bottom plan view; and,

FIG. 8 is a perspective view showing the design in use, the broken line showing is for illustrative purposes only and forms no part of the claimed design.

A pocket is formed in the front of the stuffed animal toy to hold a gift.
